AUTOMATIC VARIABLE TRAFFIC
REGULATOR

Robert O. Nelson, Los Angeles, Calif.; Anna J. Nelson, administratrix of the estate of said Robert O. Nelson, deceased, assignor, by mesne assignments, to The Engineering and Research Corporation, New Haven, Conn., a corporation of Connecticut

Application February 27, 1924, Serial No. 695,596

32 Claims. (Cl. 177—337)

This invention relates to traffic regulating devices and one of the objects is to provide an automatically variable, electrically controlled and operated mechanism for giving the right-of-way to the first vehicle approaching the intersection of two or more roads. A second object is to so construct the mechanism of the regulator that it will signal the right-of-way to waiting vehicles immediately after the crossing of the intersection by the last vehicle having the right-of-way in the other or cross direction, regardless of the length of time it may have waited if the stay is less than a predetermined period of time, such, for instance, as thirty seconds. The device is also designed so that it will limit the stopping time of a waiting vehicle to a certain predetermined number of seconds, when cross traffic has the right-of-way in the other or cross direction. Further objects will be disclosed in the course 20 of the following specification, reference being had to the accompanying drawings illustrating one practical embodiment of the invention, and in which:

Fig. 1 is a diagrammatic view of units of apparatus and the connections between the latter which provide a traffic control system;

Fig. 2 is a schematic view of a straight intersection and showing a system installed to provide for traffic regulation;

Fig. 3 is a sectional side view of one of the traffic actuated controls;

Fig. 4 shows in elevation, and in somewhat enlarged form, one of the units of apparatus as shown in Fig. 1;

Fig. 5 is a fragmentary enlarged side elevation of one of the circuit closers embraced in the unit as shown in Fig. 4;

Figs. 6 and 7 are transverse sectional views taken respectively along the lines 6—6 and 7—7, and in the direction of the arrows as shown in Fig. 4;

Figs. 8 and 9 are views similar to Fig. 7 but illustrating contact paths or circles which form a part of the unit of Fig. 4, and additional to the contact path or circle illustrated in Fig. 7;

Fig. 10 is a view similar to Fig. 4, but showing different units of apparatus from that illustrated in the preceding figure;

Figs. 11, 12, 13 and 14 are transverse sectional views taken along the lines 11—11, 12—12, 13—13, and 14—14, respectively, and in the direction of the arrows as indicated in Fig. 10; and

Fig. 15 is a view similar to Fig. 14, but showing the parts in a different position.

Referring to the drawings more particularly

and by reference characters A designates a north and south street or road or lane, which is crossed by an east and west street or lane B, and at the middle point of the intersection is a conventional signaling device C, in or under which is arranged the control box D. The signal may be of any of the well known types in which the "stop" and "go" signs are electrically lighted and alternated so that when the sign reads "stop" in one direction it will read "go" in the other or cross direction, and vice versa and thus indicate right-of-way at the intersection of the two lanes A and B. Thus in Fig. 1 I have indicated signal lamps R, R as the red or "stop" lamps for the A street, and these lamps are connected with the lamps G, G which are the green or "go" lamps of B street; while the R₁, R₁, "stop" lights for B street are connected in circuit with and are simultaneously energized with green "go" lamps G₁, G₁, which give the right-of-way to A street traffic, and stop the B street traffic.

The circuit controlling mechanism (later to be described) which controls the two circuits to the lamps in the signal, is contained within the control box D, and the traffic situation is indicated and communicated to this mechanism through auxiliary circuits which are controlled by what I conveniently term traffic actuated controls. These, as shown, may take the form of trigger switches H, I, J, K, L, M, N, and O, which are closed by the passing of vehicles over them. These switches are secured in the streets A and B and are arranged in the path of travel of the vehicles about as shown in Fig. 2. The rear switches I, K, M and O are arranged close to the intersection while the front switches H, J, L and N are preferably arranged about about sixty feet from the intersection to indicate the approach of cars from any direction. To insure the registering of each vehicle these switches are preferably arranged in groups of two duplicates arranged side by side where necessary to insure proper coverage of the path of approaching traffic, and are wide enough to insure operation by any vehicle passing thereover. The two switches forming each group are connected in parallel with each other and since both switches of each group perform identical functions, only one of each pair is indicated in Fig. 1, and it is obvious that where one switch is of sufficient width to cover the path of approaching traffic only one such switch need be used in place of the group of two arranged side by side.

The design or construction of these vehicle actuated controls may be greatly varied and mod-

ified, but a preferred form is illustrated in Fig. 3 and consists of a box or casing 16 which is imbedded in the street, and has a plate 17 pivotally secured therein as at 18. The swinging end of the plate 17 has a segmental flange 19 which frictionally contacts against a rubber strip 20, and is preferably oiled, so as to keep out snow, dirt and ice as much as possible. The plate 17 is normally retained in an inclined position, as shown, by a spring 21, but when travelled over by the wheel E of a vehicle it depresses to a flush or horizontal position where the flange 19 strikes a shelf or stop 22. A pair of switch terminals 23 and 24 are respectively secured upon the box 16 and plate 17, and come together when the plate is depressed, and thus close a circuit through wires which are led to the control box by suitable conduits.

Four circuits are controlled by the trigger switches and are respectively indicated by wires 25, 26 from switches H, J, wires 27, 28 from switches I, K, wires 29, 30 from switches L, N, and wires 31, 32 from switches M, O. The wires 25, 27, 29, and 31 are branches of the positive supply wire 33 to the entire system, and 34 designates the main negative supply wire.

Before describing the entire electrical system, the mechanisms, which, except for the trigger switches, are preferably all contained within the control box D, may be detailed as follows:

The signal timing mechanism includes a pair of magnetically actuated drums F and P which are rotatably mounted upon hollow, dead shafts 35. In the present embodiment these drums are identically constructed and therefore only one will be described. Attention being invited to Figs. 1, 2, 4, 5 and 6, it will be seen that one end of the drum is provided with a ratchet wheel 36, adapted to be successively rotated the length of one tooth by a spring pawl 37, on an armature 38 which is moved by a magnet 39. A coiled spring 40, having one end secured to the dead shaft 35 and the other end to the drum, tends to keep the drum in its initial, nonactuated, or normal position, which position is determined by a stop 41 (on the drum) which meets an extension 42 of a supporting standard 43. When the drum is in this normal position and as shown in Fig. 5, an extension of the stop 41 contacts with a spring terminal 44 and holds the latter normally away from a point terminal 45 thus keeping open a circuit through wires 46 and 47. When the magnet 39 is energized the drum is rotated, closing a circuit through wires 46 and 47. A dog 48, which is held against the ratchet wheel by a spring 49 resists the return of the drum, but a magnet 50 is arranged, when energized, to lift the dog and free it of the ratchet. A beak 51 is arranged at the other end of the dog member, and is depressed when the dog is lifted, and is so coordinated with the dog that the ratchet wheel 36 is permitted to return (by reason of the drum spring 40) the distance of one tooth by one impulse to the magnet 50.

On the surface of the drum are three pathways for brushes 52, 53 and 54, which are the terminals respectively of wires 55, 56 and 57, in drum F, and of wires 58, 59 and 60 in drum P. The contact terminals of these wires are insulated from the members mounting the same. Parts of the brush paths are insulated, as shown in black, while the remaining portions, which form contacts with the brushes, are supplied by individual wires 59, 61 and 60, in drum F, and by wires 56, 75 and 65, in drum P, and these wires are accommo-

dated by the hollow shafts or axles 35, this having been especially illustrated in Figs. 7, 8 and 9. The wires 61 and 65 are branches of the main positive wire 33. When the F drum is in normal position the circuit is open between 59 and 55, and between 57 and 60, but is closed between the wire 61 and the brush 53 and wire 56. Any position of the drum off normal reverses the open or closed conditions of these circuits. When the drum P is in normal position the circuit is open between 56 and 58, and between 65 and 68, but is closed between the wires 65 and 58. Any position of the drum off normal reverses the open or closed conditions of these circuits similar to drum F. It may here be noted (see Fig. 6) that one tooth is missing in the ratchet wheel 36, and this limits the rotations of the drum by the armature 38, but, as the number of vehicles which can register between the "approach" triggers H, J, L, and N and the "crossing" triggers I, K, M and O, is limited, due, for example, to the spacing which must be maintained between the vehicles, it is not necessary to provide for a greater number of registration teeth in the ratchet wheel. The entire magnetic escapement mechanism 48, 49, 50 and 51 is mounted on a large armature 62 pivoted as at 63. This armature, when lifted by the magnet 64, lifts the dog 48 and beak 51 so that the drum may be returned to its normal position.

The mechanical features of a pair of drums 30 designated as U and V, and illustrated in Figs. 1, 10, 11, 12, 13, 14 and 15, will now be described. Drum U consists of a shell 65 which is rigidly secured to but insulated from a "live" axle 66. A gear 67 is slidably keyed on but insulated from the axle 66, and rotates the drum when in mesh with a gear 68 which is insulated from the frame. The gear 67 is shifted into and out of mesh with the gear 68 by a fork 69 which is controlled by a solenoid 70 and a spring 71. When the solenoid 40 is energized the gears are meshed, but when de-energized the spring 71 restores the gear 67 to normal or idle position. On the surface of this drum 65 is a pathway 76 for a pair of contact brushes 72 and 73 insulated from each other, and which are carried by a rocker arm 74, tiltably mounted on a supporting rod 75. This pathway is divided into equal lengths of segmental "contact periods" and "no contact periods", which alternate on the surface. Thus, if the drum is rotated by the gear 68, it will be seen that for thirty seconds the brush 72 has active contact followed by thirty seconds of no contact, while the reverse is true for brush 73. These brushes are so arranged that when one has active contact with the drum the other does not, and vice versa, and the brush 72 has such contact when the drum is in normal position and for the first period of rotation thereof. The contact plates in the pathway are supplied by wire 78 via axle 66.

To insure the return of the drum 65, to its initial position when gear 67 is freed from the gear 68, I provide a coil spring 79, in a housing 80. This spring is under initial tension and is additionally wound up by the rotation of the shaft 66 when gears 67 and 68 are meshed. It consequently unwinds and reverses the direction of the drum when the gears are released. Either one of two stops 81 and 84, on the drum 65, engages in the initial position of the drum, with a stationary stop 82, on a dog 83 which is mounted on the rod 75, and these stops 81 and 84 are designed to slip under the member 82 when the drum is being turned by the gear 68 but stop against it when the drum is being

returned by the spring 79. Since the drum may continue to revolve indefinitely means are provided for relieving the spring 79, as follows: Escapement dogs 85 and 86, which co-act with teeth 87 and 88 on the housing 80, are mounted on the member 83 from which projects the stop 82. The housing 80 is rotatable upon the shaft 66, and is prevented from revolving, as the spring tension increases, by the engagement of dog 85 with tooth 87 or 88. As either of the teeth or stops 81 or 84 lift the stop 82 during the forward rotation of the drum 65^a, however, it releases the tooth 85 and permits the housing to rotate one half a revolution. Thus the tension of the spring 79 will be substantially uniform at all times.

The gear 68 is arranged upon a shaft 89 which is rotated by a motor T adapted to turn the shaft at a uniform speed.

As previously stated the gear 68 only meshes with the gear 67 at certain times, but it is constantly in mesh with a gear 89 of the drum V, which I will now proceed to describe. This drum consists of an axle 90 and a cylindrical member 91, rotated by the gear 89. Two pathways 92 and 93, for brushes 94 and 95, are mounted on the member 91, and these pathways and the corresponding brushes and connections are illustrated as identical in construction. The contact terminals 96 of the wires 97 and 108 are insulated from the members mounting the same. In what may be termed the initial position the terminal 96 of a wire 97, to the brush 94, will not receive a contact until one-half a revolution of the drum or pathway is completed, at which time (for instance forty seconds) it will wipe the point contact 98 (see Fig. 14), which is supplied by a wire 107, via the axle 90. These terminal points or contacts 98 and 106 are insulated from each other in their respective pathways as illustrated in Figs. 14 and 15. The axle 90 is insulated from the frame and from drum 91. If, however, a magnet 99 (or 100) is energized in the meantime the brush 94 is lifted above the contact where it is retained by a hook 101, or 102, suspended from a bar 103. Thus no contact will be formed, as shown in Fig. 15. The hooks 101 extend laterally below the surface of the pathways 92, 93, where they are tripped by diametrically opposed pegs 104, 105, just after the terminal points 98 or 106 have passed beyond the contact position with terminal 96. After the hook 101 is so tripped to allow the terminal contact 96 to rest in rubbing contact on the pathway of drum 91, the hook 101 is supported by bearing against the end of the brush 94 until the brush is again lifted by energization of magnet 99. Thus a failure of impulse to magnets 99, 100 during any forty second period will permit a point contact between the terminals of wires 107 and 97 (or 106 for magnet 100).

The circuit systems or electrical connections may be described as follows:

The main positive supply wire or cable 33, in addition to the trigger switch branches 25, 27, 29 and 31, has the branch 61, to the middle brush path of drum F; a branch 65, to the two left hand brush paths of drum P; a branch 109, to an armature 110; a branch 111, to an armature 112; the branch 107, to the shaft 90; and a branch 113 to the timer motor T. The negative supply wire 34 has a branch 114, to the signal lamps; a branch 115, to the magnet 50; a branch 116, to the magnet 64; a branch 117, to the magnet 39 (drum F); branches 118, 119 and 120 to

corresponding magnets of drum P; branches 121 and 122 of magnets 99 and 100, respectively; and a branch 123 to the timer motor T.

Assuming now that the vehicle actuated or trigger switches H or J are closed, indicating the approach of an east or west moving vehicle, two impulses (if a four wheel vehicle) will be sent through wire 26, thus energizing the magnet 39 (of drum P) and causing the drum to be rotated two teeth off normal, the negative supply to the magnet being wire 120. Brush 52 and wire 58 will now have contact with wire 56, wire 59 will break contact with wire 65, and wire 60 will have contact with wire 65. The wire 56, however, is not a live wire unless the drum F is normal, at which time the circuit will be completed through the wire 61 to the main supply wire 33. Granting this condition, the wire 58 includes in its circuit a solenoid 124, and continues as wire 125 to give a positive supply to the signal lamps R, R, 20 G and G, which signals the right-of-way to traffic traveling east and west on street B. The wire 59 which, when the drum P is normal, gives a positive supply to the contact plate in path 126 of drum F, is now dead. The wire 60 which now 25 has a positive supply from wire 65 gives a positive supply to contact plate in path 127 of drum F but that is as far as it gets since there is no contact with wire 57 when drum F is normal. Now as the vehicle proceeds to cross the intersection it depresses and closes the trigger switches I or K and the consequent impulses in wire 28 causes the magnet 50 (drum P) to lift the escapement 48 twice, thus releasing the drum two teeth back to normal. In normal position 35 again, the wire 58 becomes dead, the signal lights go out, the wire 59 gets a positive supply, and the wire 60 is dead.

The action is the same in drum F when a vehicle is crossing the intersection either north or south. The wire 30 carries impulses that put drum F off of normal. The wire 55 now becomes positive charged, if the drum P is normal, and energizes a solenoid 135, and continues as wire 129 to give a positive supply to the signal lamps 40 R1, R1 of east and west traffic, and G1, G1 to north and south traffic. The wire 56 which gives a positive supply to contact plate in brush path 130 of drum P, is now dead. The wire 57, which now has connection with wire 60, still remains 45 dead since the wire 60 is dead when drum P is normal. When the vehicle now has depressed the crossing switch O or M, the consequent impulses in wire 32 cause the magnet 50 (drum F) to lift the escapement twice, and this releases the 50 drum so that it can return back the distance of 55 two teeth to normal.

It will thus be seen that when both drums F and P are off normal, the wires 55, 56 and 58 are dead, and the wires 60 and 57 are live with a 60 positive charge. The wire 57 includes in its circuit the solenoid 70 which brings the drum U into rotation by intermeshing of gear 67 with the gear 68, this circuit being as follows: Line 33, wire 65, brush 54, wire 60, segment 127, brush 65 65 54, wire 57, solenoid 70, wire 71, axle 66, segment 76, through one of the brushes 72 or 73 and corresponding wires 132 or 133, through one set of contacts on the contact arm 134, through one set of lamps, to wire 114, and return wire 34. This 70 circuit also charges the contact plates of the path 76, one of which is in contact with either brush 72 or 73 as the drum rotates, and thus alternates the supply in wires 132 and 133, at intervals of thirty seconds. The first current of 75

supply, however, passes through the brush 12 and wire 132. The wires 132 and 133 end in terminals on a switch arm 134, which is swung to one side or the other by solenoids 124 and 135, when either is energized. A spring 136 is arranged to act against two angular surfaces of the arm and tends to yieldingly retain it in whichever position last pulled by the solenoids. The result is that whichever drum F or P was off, normal first, would have caused its solenoid, via wires 55 or 58, to have pulled the arm to that side, and consequently when the other drum is off normal both solenoids would be dead and the arm 134 would remain where it was last attracted. Terminal wires 131, 138, 139 and 140 are so arranged and connected that the wire 132, during the first period of charge, would supply the signal lamps of the first drum to go off normal, and the wire 133 would connect with the signal lamps of the other drum. Thus, as long as both drums are off normal the signal lamps will alternate the traffic right-of-way at thirty second intervals.

It is evident that traffic is far from uniform, and that odd arrangements of wheels, horse drawn vehicles and motor cycles, etc., would not always give the same number of impulses at both crossings and approach trigger switches. As long as traffic is waiting in both directions, so that both drums F and P are off normal, there will be no difficulty, as the signals would continually operate and alternate at thirty seconds intervals. When, however, a drum is off normal, and no traffic is waiting to cross in the direction signaled, complications which would disqualify the entire system might result; and to overcome this I provide the drum V, the function of which might be described as follows:

The magnets 98 and 100 are energized simultaneously with the drum magnet 39, via wires 30 and 26, respectively, wires 121 and 122 giving the negative supply. Now, as previously explained, if no impulse is received in, for instance, magnet 98 via wire 30, during any forty seconds intervals, contact 96 will remain on bar 92 and an impulse is sent through wire 97 from wire 101. This passes to a magnet 142, and the switch 44-45 (if the drum F is off normal) to the magnet 64. The magnet 142 lifts the armature 50 or contact terminus 110 of the positive supply wire 109, to insure a steady supply in the wire 97 until the drum F is restored to normal, which represents no traffic waiting in the direction represented, and this should be correct if no crossing is made within forty seconds after the approach impulse.

It should be understood that in expressions such as "within a time limit", "within a predetermined time", and the like, occurring in some of the claims, the term "within" is used broadly as the equivalent of "not later than" in the sense that it includes the last instant of time.

Thus, among others, the several objects of the invention as specifically afforded are achieved. As before brought out, numerous changes in structure and rearrangement of the parts might be resorted to without departing from the spirit of this invention; it being obvious that the system may be amplified or modified both functionally and structurally according to the means at the intersection where the particular installation is being made.

What is claimed as new, and desired to be protected by Letters Patent, is:

75. 1. A traffic control system for the intersection

of traffic lanes, said system including signalling means to accord and interrupt right-of-way to traffic approaching the intersection in such lanes, operating means for said signalling means, vehicle actuatable controls disposed in said lanes in advance of the intersection, means for connecting said controls to said operating means for operation of the latter to cause the signalling means to afford right-of-way to either one only of said lanes upon actuation only of the control 10 therein, time controlled means for preventing accord of right-of-way to said one lane beyond a determined time interval of absence of actuation in both lanes after and measured from any such actuation of said control in said one lane, and further time controlled means forming a part 15 of said operating means and responsive to actuation of the vehicle actuated control in a second lane for causing—in the event of continued control actuations in said one lane—said operating 20 means to transfer right-of-way to said second lane prior to expiration of the determined interval as timed by the first mentioned time controlled means.

2. A traffic control system for two intersecting 25 streets including in combination electric signals normally deenergized and adapted when energized to display indications to accord right-of-way to the respective streets, traffic actuatable means located at a distance from the intersection 30 in each of said streets and adapted to be actuated momentarily by the passage of traffic thereby in approaching the intersection, rotary switching mechanism connected to said signals and traffic actuatable means and having signal 35 interlocking means including separate switching positions for the respective signals to prevent concurrent energization of the right-of-way signals in both streets, said mechanism including means operated by momentary actuation of the 40 traffic actuatable means in either one only of said streets to immediately operate said switching mechanism to one position to energize one of said signals to accord right-of-way to said one street, and means operated by following actuation in said one street while right-of-way is 45 so accorded to maintain such right-of-way, said mechanism also including means operated by momentary actuation of traffic approaching on the other street after the one street and while 50 right-of-way is accorded to said one street to condition said mechanism for subsequent transfer of energization to the right-of-way signal on said other street in the other position of said switching mechanism and to maintain said mechanism so conditioned to cause transfer of right-of-way to said other street immediately upon cessation of traffic on said one street, said control mechanism also including means for assuring deenergization of said signals again following said transfer within a time limit from cessation of traffic in said other street while traffic is 55 absent from said one street.

3. A vehicle control system for the intersection 60 of two vehicle lanes including signalling means to accord and interrupt right-of-way in such lanes, operating means for said signalling means, means responsive to the approach of a vehicle toward said intersection over either one of such lanes to cause said operating means to 65 accord right-of-way through said signalling means to said vehicle in said one lane and to maintain such right-of-way in the case of closely spaced vehicles following the first vehicle in the same lane, means forming a part of said oper- 70

ating means and responsive to the approach of a vehicle in the second of the two vehicle lanes to transfer right-of-way through said signalling means to said second lane upon the spacing of 5 such vehicles in said one lane exceeding a predetermined amount while said one lane has right-of-way in its favor, and timing means connected with said operating means and said signalling means to cause transfer of right-of-way to said 10 second lane within a maximum time limit from such approach of traffic in said second lane as indicated by the responsive means and in the event that the right-of-way is maintained up to such limit on said one lane by vehicles thereon 15 whose spacing does not exceed such predetermined amount.

4. A traffic control system for the intersection of two vehicle lanes, including signalling means to accord and interrupt right-of-way and transfer right-of-way between such lanes, means responsive to the approach of a vehicle only in one of such lanes to operate said signalling means to accord right-of-way to said one lane and interrupt right-of-way in the second lane, means responsive to the subsequent approach of a vehicle in said second lane while right-of-way is so accorded to said one lane to potentialize said signalling means for transferring right-of-way to said second lane, means responsive to the approach of additional vehicles in said one lane following the first vehicle therein while right-of-way is so accorded to said one lane to cause said signalling means to prolong such accord of right-of-way in said one lane and delay such transferring 35 of right-of-way, and means providing a maximum time limit to such prolongation of accord of right-of-way from such potentialization whereby transfer of right-of-way to said second lane is assured within said time limit.

40 5. A traffic control system for the intersection of two vehicle lanes, including signalling means to accord and interrupt right-of-way and transfer right-of-way between such lanes, means responsive to the approach of a vehicle only in one of such lanes to operate said signalling means to accord right-of-way to said one lane and interrupt right-of-way in the second lane, means responsive to the subsequent approach of a vehicle in said second lane while right-of-way is so accorded 45 to said one lane to potentialize said signalling means for transferring right-of-way to said second lane, means responsive to the approach of additional vehicles in said one lane following the first vehicle therein while right-of-way is so accorded to said one lane to cause said signalling means to maintain right-of-way in said one lane longer than by said first vehicle and to correspondingly delay such transferring of right-of-way, and means for causing transfer of right-of-way to said second lane at a predetermined time limit from such potentialization in the event right-of-way is so maintained by additional vehicles in said one lane up to such time limit.

6. A traffic control system for intersecting 45 streets including in combination right-of-way signalling means for the respective streets, traffic responsive means in each street, rotary switching devices one for each street, each switching device having a normal inactive position and an off normal position and adapted to be rotated from said normal position to said off normal position by traffic approaching on its associated street, a time limit release mechanism connected to each of the respective traffic responsive means to have 75 the time limit reset by traffic actuation of the

latter means and connected with each such device for returning it to normal position within a time limit from any cessation of traffic approaching on its associated street, energizing circuits for the respective right-of-way signals passing through both of the switching devices so as to operate the signalling means to accord initially right-of-way to whichever street has its rotary switching device off normal only while the other device is on normal and to prevent accord of right-of-way to the other street and maintaining said right-of-way even though said other device is subsequently rotated to off normal position while said first device is off normal, and locking members associated with said devices for maintaining said other device off normal when so rotated by traffic approaching in said other street and waiting for right-of-way while the first mentioned device is off normal, whereby subsequent accord of right-of-way to said other street is assured upon return of the first device to normal position within the time limit of the release mechanism of said other device.

7. A traffic control system for intersecting streets, including in combination right-of-way signalling means, rotary switching devices one for each street, each switching device having a normal inactive position and a plurality of successive off normal positions and adapted to be rotated from said normal position and through a number of said off normal positions by vehicles approaching on its associated street the number of such latter positions through which it is rotated being proportional to the number of such vehicles, means in the switching devices cooperating to operate the signalling means to accord right-of-way in whichever street has its rotary switching device off normal while the other device is on normal, and means connected with each said rotary switching device to restore it back through such successive off normal positions to normal position upon the passage of all such traffic from its associated street.

8. A traffic control system for intersecting streets, including in combination, right-of-way signalling means, traffic responsive means in each street and including one means located at a distance from the intersection and adapted to be actuated by traffic approaching the intersection on the street and another located near the intersection and adapted to be operated by traffic crossing the intersection on such street, rotary switching devices, one for each street, having a normal position and a plurality of successive off normal positions for operating said signalling means, means operated by a plurality of actuations of the distant responsive means in either one street only to rotate its associated switching device from normal position through a number of such off normal positions corresponding to the number of such actuations, means connected with said device to maintain it in off normal position after each such actuation, and means operated by a corresponding plurality of actuations of the near responsive means in said one street to interrupt said last named means and cause said device to return back through such off normal positions to normal position, and means operated by said device in its off normal position, to operate said signalling means to accord right-of-way to said one street, whereby right-of-way is normally accorded to said one street upon traffic actuation only on said one street and until all such approaching traffic in said street has crossed the intersection.

9. In a traffic signal system for intersecting streets, a signal device for indicating "go" and "stop" signals on the streets, means for substantially immediately initiating the operation of the signal device upon an impulse received when a vehicle approaches the intersection from either one of the streets, and means for causing the "go" signal to be given only to the street first receiving an impulse and then causing the "go" signal to be given only to the other street receiving a subsequent impulse while the "go" signal is so indicated to the first street, each for predetermined periods beginning with the first impulse on said other street and in response to subsequent impulses received by the signal initiating means for both streets and continuing throughout said predetermined periods.

10. A traffic control system for two intersecting streets, including in combination electric signals normally deenergized and adapted when energized to display indications to accord right-of-way to the streets, control mechanism for operating said signals responsive to traffic in the streets, said mechanism having means to prevent concurrent energization of the right-of-way signals in both streets, and including means responsive to traffic approaching on only one of the streets to immediately energize one of said signals to accord right-of-way to said street and maintain said one signal so energized in response to further traffic in said one street, and means responsive to traffic approaching on the other street after the one street and while right-of-way is accorded to said one street to condition said mechanism to cause subsequent transfer of right-of-way to said other street immediately upon cessation of traffic on said one street, and means for assuring deenergization of said signals within a time limit from cessation of traffic in both streets.

11. In a traffic signal system for intersecting streets, a signal device for indicating "go" and "stop" signals to each street, means associated with one street for receiving energizing impulses from traffic on said street for operating the signal device to indicate "go" to that street and "stop" to the cross street, means associated with the cross street for receiving energizing impulses from traffic on said cross street to operate the signal device to indicate "go" to the cross street and "stop" to said one street, and means cooperating with both of said impulse receiving means and operated when the means associated with said cross street is energized subsequently to the means associated with said one street and as long as both remain energized to determine the maximum time at which "go" signal indication shall be so taken from said one street and given to said cross street in response to and measured from the first of said impulses received by said cross street means.

12. In a traffic signal system for intersecting streets, a signal device for alternately indicating "go" signals to one street and "stop" signals to the cross street, impulse receiving means for one street and associated means in said one street for energizing said impulse receiving means to substantially immediately indicate "go" on one street and "stop" on the cross street in response to traffic solely on said one street, impulse receiving means for the cross street and associated means in the cross street for energizing said means subsequently to cause "go" to be indicated to said cross street and "stop" to said one street in response to traffic on said cross street, and

means for associating the concurrent operation of said impulse receiving means for said streets including a timing means to determine the maximum time at which the "go" signal shall be given to the cross street and the "stop" signal to said one street in response to and measured from the impulse received by said cross street means and the maximum time at which the last-named signals are reversed in response to and measured from a further impulse from said one street, whereby "go" and "stop" signals shall be alternately given to said streets at maximum times when the impulse receiving means are repeatedly and concurrently energized.

13. A vehicle control system to be installed at the intersection of two vehicle lanes including signalling means to accord and interrupt right-of-way to vehicles moving over such lanes, operating means for said signalling means, means responsive to the approach of a vehicle over one of said lanes to cause said operating means to function to accord through said signalling means right-of-way to such vehicle and to maintain such right-of-way in the case of vehicles following the first vehicle in the same one lane and within a predetermined spacing interval from said first vehicle and from each other, means responsive to the approach of a vehicle over the second of the two lanes to potentialize said operating means for transfer of right-of-way to said second lane, and means forming a part of said operating means to assure that such transfer of right-of-way to said second lane will occur before the expiration of a predetermined interval of time measured from and following such operation of the vehicle responsive means in said second lane regardless of the vehicles following within such predetermined spacing in said one lane.

14. A traffic control system to be applied at the intersection of two vehicle lanes and including signalling means having right-of-way according means and right-of-way interrupting means for each lane, operating means for said signalling means, vehicle actuatable means in each lane and connected to said operating means, normally inoperative timer means for activating when operative said operating means for alternating through said signalling means the right-of-way between the said lanes for predetermined periods, and means responsive only to substantially continuous vehicle actuation on both lanes to cause said timer means to become and be maintained operative to time said periods, said timer means becoming inoperative again immediately upon cessation of vehicle actuation in one of said lanes.

15. A traffic control system to be applied at the intersection of two vehicle lanes and including signalling means having right-of-way according means and right-of-way interrupting means for each lane, operating means for said signalling means, vehicle actuatable means in each lane and connected to said operating means, normally inoperative timer means for activating when operative said operating means for alternating through said signalling means the right-of-way between the said lanes and for maintaining such right-of-way for predetermined times, and means responsive to vehicle actuation on both lanes to cause said timer means to become operative, and means responsive to subsequent cessation of vehicle actuation only on a lane to which right-of-way is accorded to cause said timer to return to inoperative condition and to cause substan-

- tially immediate transfer of right-of-way to the other lane.
16. A traffic control system for two intersecting streets, including in combination, electric signals adapted to be illuminated when energized to display indications according right-of-way in one street while interrupting right-of-way in the other street, control mechanism for maintaining said signalling means normally deenergized in the absence of traffic on either street, and operating to energize said signals immediately in response to the approach of traffic only on said one street, and means operated by the approach of traffic on said other street when said signals are so energized to provide a time limit to such energization of said signals from such approach of traffic on said other street to assure deenergization of such signals interrupting right-of-way in said other street within such time limit.
17. A traffic control system for two intersecting streets, including in combination electric signals adapted to be illuminated when energized to display indications according right-of-way in one street while interrupting right-of-way in the other street, control mechanism for maintaining said signalling means normally deenergized in the absence of traffic on either street, and operating to energize said signals immediately in response to the approach of traffic only on said one street and to maintain such signals energized in the event of closely spaced following traffic in said one street, and means operated by the approach of traffic on said other street, when said signals are so energized to provide a time limit to such energization of said signals from such approach of traffic on said other street to assure deenergization of such signals interrupting right-of-way in said other street within such time limit, in the event of continuation of approach of such following traffic.
18. A traffic control system for two intersecting streets, including in combination electric signals normally deenergized and adapted when energized to display indications to accord right-of-way alternately to the streets, control mechanism responsive to traffic in the streets and operating in response to traffic only on one street to energize said signals immediately to accord right-of-way to said one street, and adapted to operate in response to traffic only on the other street to energize said signals immediately to accord right-of-way to said other street, and means associated with said control mechanism to cause alternation of right-of-way at determined time intervals through said signals in the event of continued approach of traffic in both streets.
19. A traffic control system for two intersecting streets, including in combination electric signals normally deenergized and adapted when energized to display indications to accord right-of-way alternately to the streets, control mechanism responsive to traffic in the streets and operating in response to traffic only on one street to energize said signals immediately to accord right-of-way to said one street, and adapted to operate in response to traffic only on the other street to energize said signals immediately to accord right-of-way to said other street, and means associated with said control mechanism to cause alternation of right-of-way at determined time intervals through said signals in the event of continued approach of traffic in both streets, and protective means to insure deenergization of said signals within a maximum time limit after cessation of traffic in both streets and if such signals remain energized up to such limit.
20. A traffic control system for two intersecting streets, including in combination electric signals normally deenergized and adapted when energized to display indications to accord right-of-way alternately to the streets, control mechanism responsive to traffic in the streets and operating responsive to traffic approaching on only one of the streets to immediately energize said signals to accord right-of-way to said street, and means responsive to traffic approaching on the other street after the one street and while right-of-way is accorded to said one street to cause transfer of right-of-way to said other street immediately upon cessation of traffic on said one street, and means connected with said control mechanism and operating within a predetermined time after and beginning with such traffic approaching on said other street to cause transfer of right-of-way to said other street in the event of continued traffic approaching on said one street during such predetermined time.
21. A traffic control system for intersecting streets, including in combination right-of-way signalling means for the respective streets, traffic responsive means for each street, rotary switching devices one for each street, each switching device having a normal inactive position and connected with the traffic responsive means of its associated street so as to be rotated to an off normal position by traffic approaching on its associated street, energizing circuits for the respective right-of-way signals passing through both said switching devices to operate the signalling means to accord right-of-way in whichever street has its rotary switching device off normal while the other device is on normal, and a timed rotary switching mechanism having an energizing circuit closed through both said devices only in their off normal positions and having alternate switching positions to energize the said right-of-way signal alternately to accord right-of-way alternately first to the street whose device was first off normal, and then to the other street for determined time intervals and a time limit release mechanism for said devices and connected to the respective traffic responsive means to have the time limit reset by actuation of the latter means and connected to the respective said devices so as to return the latter to normal position at the expiration of such time limit after an actuation in the absence of resetting of said time limit by a subsequent actuation within such time limit.
22. A traffic control system for intersecting streets, including in combination right-of-way signalling means, traffic responsive means in each street and including one means located at a distance from the intersection and adapted to be actuated by traffic approaching the intersection on the street and another located near the intersection and adapted to be operated by traffic crossing the intersection on such street, rotary switching devices for operating said signalling means and having a normal inactive position and a plurality of successive off normal positions, one such device being provided for each street, means operated by one actuation of the distant responsive means in one street to rotate its associated switching device to the first off normal position and by subsequent actuations of said distant responsive means to rotate said device successively through said successive off normal positions, means operated by each actuation of the near

responsive device to rotate said device back one position toward normal whereby after all traffic which approached has passed the said device will be restored to said normal position, and means 5 operated by said device in its off normal position to operate said signalling means to accord right-of-way to said one lane.

23. A traffic control system for intersecting streets, including in combination right-of-way 10 signalling means for the respective streets, traffic responsive means in each street and including one means located at a distance from the intersection and adapted to be actuated by traffic approaching the intersection on the street and 15 another located near the intersection and adapted to be operated by traffic crossing the intersection on such street, rotary switching devices one for each street having a normal position and an off normal position for operating said signalling means, and means operated by actuation 20 of the distant responsive means in one street to rotate its associated switching device to off normal position, a locking member connected with said device to maintain it in off normal position 25 after such actuation, and means including a release member for said locking member operated by actuation of the near responsive means in said one street to interrupt said locking member and cause said device to return to normal position, 30 energizing circuits for said signals passing through said switch devices such that one circuit is energized by said device in its off normal position to operate said signalling means to accord right-of-way to said one lane, and a time 35 limit release mechanism for said device and connected to the distant responsive means to have its time limit reset by actuation of the latter so as to operate within a time limit after the last such actuation of the distant responsive means 40 to restore said device to its normal position in the event it has not been already restored by actuation of the near responsive means.

24. A traffic control system for intersecting streets, including in combination right-of-way 45 signalling means, traffic responsive means in each street and including one means located at a distance from the intersection and adapted to be actuated by traffic approaching the intersection on the street and another located near the intersection and adapted to be operated by traffic 50 crossing the intersection on such street, rotary switching devices one for each street having a normal position and an off normal position for operating said signalling means, and means operated by actuation of the distant responsive 55 means in one street to rotate its associated switching device to off normal position, means connected with said device to maintain it in off normal position after such actuation, and means operated by actuation of the near responsive 60 means in said one street to interrupt said last named means and cause said device to return to normal position, means operated by said device in its off normal position to operate said signalling means to accord right-of-way to said 65 one lane, and a timed cyclic signal switch connected to said signalling means and having an energizing circuit connected with the several switching devices and so as to be operated by 70 the latter when they are all off normal to cause right-of-way to be successively accorded to the streets for predetermined time intervals.

25. A traffic control system for the intersection of two traffic lanes and including signalling means 75 for according and interrupting right-of-way to

the said lanes, normally inactive timer means operative when active to cause said signalling means to alternately accord right-of-way to the several lanes and for timing the alternating periods of right-of-way, means responsive to the approach of a vehicle in only one lane to cause accord of right-of-way substantially immediately to said one lane and means responsive only to the approach of a vehicle in the second lane while right-of-way is so accorded to said one lane to render 10 said timer active to start such timing.

26. A traffic control system for the intersection of two traffic lanes and including signalling means for according and interrupting right-of-way to said lanes, traffic actuatable means in each lane, 15 operating means for said signalling means to cause accord of right-of-way to either lane in which the traffic actuatable means is first actuated, means forming a part of said operating means and operable upon actuation in either one 20 lane while right-of-way is so accorded to the other lane to assure the transfer of right-of-way from said other lane to said one lane within a predetermined maximum period from such actuation in said one lane in the event of continued 25 accord of right of way to said other lane up to such maximum.

27. A traffic control system for intersecting traffic lanes and including signalling means for according and interrupting right-of-way to said 30 lanes, operating means for said signalling means and including one mechanism responsive to the approach and passage of individual vehicles in one of said lanes so as to accord right-of-way to said one lane upon the approach of such vehicles and 35 to terminate right-of-way upon the passage of such vehicles, a corresponding mechanism for the other lane, interconnecting means to prevent the according of right-of-way to one lane while right-of-way is accorded to the other lane, and time 40 controlled means for terminating right-of-way on either lane to which it is accorded within a predetermined time limit after the last vehicle approaches on such lane and in the event such right-of-way is not previously terminated by action of said mechanisms upon passage of traffic.

28. A traffic control system for intersecting traffic lanes and including signalling means for according and interrupting right-of-way to said 45 lanes, operating means for said signalling means and including one mechanism responsive to the approach and passage of individual vehicles in one of said lanes so as to accord right-of-way to said one lane upon the approach of such vehicles and to terminate right-of-way upon the passage 50 of such vehicles a corresponding mechanism for the other lane, interconnecting means to prevent the according of right-of-way to one lane while right-of-way is accorded to the other lane, and time controlled means for terminating right-of-way on either lane to which it is accorded within a predetermined time limit after the last vehicle approaches on such lane and in the event such right-of-way is not previously terminated by action of said mechanisms upon passage of traffic 55 and further time controlled means operable as long as both of said mechanisms are operated in response to the approach of traffic to alternate right-of-way between the lanes of said mechanisms for predetermined times.

29. A traffic control system to be applied at the intersection of two vehicle lanes and including signalling means for according and interrupting right-of-way to the said lanes, normally inactive timer means operative when active to cause said 70

- signalling means to display right-of-way alternately to the lanes and for timing the period of such alternating display, and means responsive solely to vehicles concurrently present in both 5 lanes for immediately activating said timer means for starting such timing.
30. In a traffic signal device, the combination with a signal adapted to be disposed at the intersection of two or more thoroughfares and having 10 traffic directing means thereon adapted to be displayed alternately to direct traffic to proceed on one thoroughfare and restraining traffic on another thoroughfare, a traffic operated device for one of said thoroughfares, means actuated by operation of said device for setting the signal to direct traffic to proceed on said thoroughfare, a traffic operated device on the other thoroughfare, means actuated by operation of said last mentioned device for setting the signal for traffic to 15 proceed on said last mentioned thoroughfare, means actuated by operation of said first mentioned traffic operated device in so setting the signal and in a plurality of subsequent operations thereof while the signal is so set for preventing 20 the signal being set by operation of said last mentioned traffic operated device for a certain definite period of time, and means whereby said means actuated by operation of said last mentioned traffic operated device will change the signal 25 as soon as said period of time has elapsed to direct traffic to proceed on the thoroughfare in which said last mentioned traffic operated device is located.
31. A vehicle control system to be arranged at 30 the intersection of two vehicle lanes and comprising signalling means including right-of-way according means and right-of-way interrupting means for each lane, operating means for said signalling means, vehicle actuated means associated with said lanes and connected to said operating means to govern the functions of the latter 35 and to control said signalling means to accord right-of-way to that lane over which a vehicle is approaching the intersection subsequent solely to the operation of the vehicle actuated means of such lane by such vehicle, means for maintaining the right-of-way so accorded, further vehicle actuated means in such lane for releasing the right-of-way maintaining means so as to extinguish such right-of-way, upon passage of such vehicle and means forming a part of said operating 40 means and functioning in absence of proper operation of said further vehicle actuated means to extinguish the right-of-way so accorded within a predetermined time interval after the last operation of the first named vehicle actuated means. 45
32. A vehicle control system to be arranged at the point of intersection of two vehicle lanes and comprising signalling means for according and interrupting right-of-way in each lane, operating means for said signalling means, vehicle actuated 20 means associated with said lanes and connected to said operating means to govern the functions of the latter to control said signalling means to substantially forthwith accord right-of-way to that lane over which a vehicle is approaching the 25 intersection and in response to the operation of the vehicle actuated means of such lane, means for maintaining the right-of-way so accorded, means functioning in response to operation of the vehicle actuated means of the second lane and 30 during right-of-way period of such first lane to potentialize said operating means to transfer right-of-way to said second lane, and means acting upon the expiration of a predetermined period of time from such operation of the vehicle actuated means in the second lane to cause such transfer of right-of-way by said signalling means in the event the operating means has continued 35 to give the right-of-way to such first lane. 40

ROBERT O. NELSON.

CERTIFICATE OF CORRECTION.

Patent No. 2,135,525.

November 8, 1938.

ROBERT O. NELSON.

It is hereby certified that error appears in the printed specification of the above numbered patent requiring correction as follows: Page 2, second column, line 69, for "drum 65" read drum 65^a; page 4, first column, line 40, for "magnet" read magnets; and second column, line 9, claim 1, for the word "afford" read accord; line 11, same claim, after "therein" and before the comma, insert and maintain right of way in said one lane by continued actuations only of the control therein; line 16, after "means" insert having a shorter time period than the first time controlled means and; line 19, same claim 1, after "lane" insert during accord of right of way to said one lane; page 6, first column, line 68, claim 12, before "substantially" insert operate the signal device to; lines 72 and 73, same claim, for "said means subsequently to" read the latter impulse receiving means subsequently to operate said device to; and second column, line 1₄, for "given" read transferred; lines 7, 8, 9 and 10, same claim 12, for "and the maximum time at which the last-named signals are reversed in response to and measured from a further impulse from said one street" read in the event that the latter impulse occurs while "GO" is indicated to said one street and to determine the maximum time at which the signals so transferred are thereafter next reversed; line 1₄, after "concurrently" insert so; and that the said Letters Patent should be read with this correction therein that the same may conform to the record of the case in the Patent Office.

Signed and sealed this 2nd day of January, A. D. 1940.

(Seal)

Henry Van Arsdale,
Acting Commissioner of Patents.
